UNITED STATES PATENT OFFICE.

PAUL BABLE, OF LOS ANGELES, CALIFORNIA.

SHOE-CLOSURE.

1,297,986.

Specification of Letters Patent. Patented Mar. 25, 1919.

Application filed December 27, 1917. Serial No. 209,105.

To all whom it may concern:

Be it known that I, PAUL BABLE, a citizen of the United States, residing at Los Angeles, in the county of Los Angeles, State 5 of California, have invented certain new and useful Improvements in Shoe-Closures; and I do hereby declare the following to be a full, clear, and exact description of the invention, such as will enable others skilled in 10 the art to which it appertains to make and use the same.

This invention relates to improvements in shoes and particularly to the closures therefor.

15 One object of the present invention is to provide a novel and improved form of closure which can be more quickly and easily laced up and unlaced than with the laced shoes now in use.

20 Another object of the invention is to provide a closure and lacing therefor which can be readily adjusted for insteps of various heights.

25 Other objects and advantages will be apparent from the following description when taken in connection with the accompanying drawing.

In the drawing:

30 Fig. 1 is a side elevation of a shoe made in accordance with my invention.

Fig. 2 is a front elevation of the same.

Fig. 3 is a sectional view taken on the line 3—3 of Fig. 2.

35 Fig. 4 is a front elevation of the shoe showing the closure in open position.

Referring particularly to the accompanying drawing, 10 represents a shoe having the closure flaps 11 and 12. In the flap 11 there are formed a longitudinal series of 40 transverse openings or slots 13, the uppermost one 13' of which is disposed at an angle to the remainder, or approximately at right angles to the upper edge of the shoe. In the other flap 12, of the closure, and adjacent 45 the edge thereof, are formed the longitudinal series of transverse openings or slots 14, the same being so arranged with respect to the openings 13 that they will be in registry when the flap 11 is brought down over the 50 flap 12 and for interlacing of the single strap 15. This strap is secured in the vamp of the shoe, as shown at 16. Intermediate the openings 14, and in a line slightly nearer the edge of the flap 12, there are formed

the additional slots 17. A second slot 18 is 55 formed adjacent the slot 13' for purpose of adjustment of the free end of the strap around the wearer's ankle.

Secured to the upper end of the flap 11, at a suitable distance from the edge thereof, is 60 a buckle 19, through which the free end of the strap is passed after being engaged around the ankle of the wearer, as clearly shown in Figs. 1 and 2 of the drawing.

As will be readily understood from an 65 inspection of the drawing, the strap is interlaced through the slots of the two closures and after the end of the strap is passed around the ankle it is engaged with the buckle. Thus a neat and smooth front is 70 produced and one without the uncomfortable hooks which press into the ankle. By lacing the strap through either series of slots in the closure flap 12, the shoe may be easily and comfortably adjusted to the foot and 75 ankle of the wearer.

When the shoe is to be taken off it is only necessary to release the end of the strap from the buckle and pull the flaps apart, the strap being of sufficient length to remain in all of the slots after the shoe has been taken off. The shoe, when put on is adjusted by simple pulling on the free end of the strap and engaging the strap around the ankle after which the terminal is engaged with the buckle. 85

What is claimed:

In a closure, the combination with a shoe upper having a plurality of longitudinal series of transverse slots disposed with their 90 corresponding slots in groups, of a flap shiftable and overlappable with respect to the shoe upper and having a longitudinal series of single transverse slots and positioned and spaced to register with the separate series of slots of the shoe upper when the flap is correspondingly shifted, a strap secured to the flap and interlaced through the slots of the shoe upper and the flap, and means for securing the other end of the strap 95 to the flap at the other end thereof. 100

In testimony whereof, I affix my signature in the presence of two witnesses.

PAUL BABLE.
